UNITED STATES PATENT OFFICE.

HENRY SHAPIRO AND ISAAC JOFFE, OF NEW YORK, N. Y.

SEWING-MACHINE.

1,358,471.

Specification of Letters Patent.

Patented Nov. 9, 1920.

Application filed April 17, 1919. Serial No. 290,779.

To all whom it may concern:

Be it known that we, HENRY SHAPIRO and ISAAC JOFFE, citizens of Russia and the United States, respectively, and residents of New York, in the county of New York and State of New York, have invented certain new and useful Improvements in Sewing-Machines, of which the following is a specification.

10 The present invention relates to improvements in sewing-machines, and more particularly to power transmitting devices for use with power-benches, carrying a number of sewing-machines, driven independently from a rotating shaft, that is disposed underneath the table portion of the bench.

One of the objects of the invention is to protect the operator from the rotating parts of the power transmitting apparatus by housing the same in a casing, that carries the clutch operating and brake actuating mechanism, so that transmission of power becomes impossible in case the casing, as a whole, or a part thereof is removed from the mechanism.

Another object of the invention is to so construct the transmitting mechanism that its driving shaft rotates within a tubular body, that serves to sustain the power transmitting apparatus, the end thrust of the elements of the said apparatus being taken up by the said tubular body and stationary parts of the bench, whereby the said shaft has no other function but to transmit rotation to the driving elements of the power transmitting apparatus, and the operation of any one power transmitter on the bench does in no way interfere with or affect the operation of other transmitters thereon.

A further object of the invention is to produce a power transmitting apparatus of the character described, which is simple in construction, efficient in operation and which can be manufactured on a commercial scale or, in other words, one which is not so difficult to produce as to be beyond the reasonable cost of such a mechanism.

With these and other objects in view, which will more fully appear as the nature of the invention is better understood, the same consists in the combination, arrangement and construction of parts hereinafter described, pointed out in the appended claims and illustrated in the accompanying drawings, it being understood that many changes may be made in the size and pro-

portion of the several parts and details of construction within the scope of the appended claims without departing from the spirit or sacrificing any of the advantages 60 of the invention.

A few of the many possible embodiments of the invention are illustrated in the accompanying drawings, in which:

Figure 1 is a front elevation of a portion 65 of a work-bench, containing the improved power transmitting apparatus; Fig. 2 is a side elevation thereof; Fig. 3 is a central vertical section taken through the power transmitting apparatus, on a larger scale; 70 Fig. 4 is a section taken on line 4-4 of Fig. 3; Fig. 5 is a section taken on line 5-5 of Fig. 3; and Figs. 6 to 8, inclusive, are central longitudinal sections taken through modified power transmitting devices. 75

Referring now first to Figs. 1 to 5, inclusive, of the drawings, the numeral 10 indicates a bench, comprising a table portion 11, that is mounted upon legs 12. The legs are each made of two sections, that is an upper 80 section 13 and a lower section 14, which are adjustably secured together by bolts 15, or similar fastening devices, so as to permit the heights of the standards to be varied according to the requirements. In the table 85 portion is provided a longitudinally extending trough 16, into which the finished goods are thrown by the operators. Upon the table portion are mounted sewing-machine heads 17, arranged in two rows, one row on each side of the trough and each row being actuated from a driving shaft 18, the said two shafts being, preferably, independent of each other, each being coupled to a motor 19 of any suitable type, the said motors 90 being disposed upon shelves 20 on one end of the work bench. The sewing-machine heads are arranged in such a manner that one of the same is disposed on each side of the trough 16 between two adjacent legs 100 12. It is obvious that, while in the drawings two rows of sewing-machines have been shown, one row may be employed if desired, and, inasmuch as each row is driven from a driving shaft that is independent 105 of the other, the construction of one row only need be discussed herein.

The shaft 18 is connected by a coupling 21 with the motor 19 and may be made of a plurality of sections, suitably joined. The 110 said shaft is journaled in bearings 22, which are mounted in any preferred manner on

hangers 23, carried by the upper sections 13 of the legs 12. There is one hanger associated with each leg 12, as clearly appears from Fig. 1 of the drawings.

- 5 With each sewing-machine head co-operates a power transmitting apparatus 24, disposed adjacent one of the legs 12. This apparatus includes a pulley 25, that is shiftably mounted in a manner presently to be described upon the shaft 18 and disposed in alignment with a pulley 26 on the machine head, through which power is transmitted for operating the stitch-forming and feeding mechanism. Over the said pulleys runs a belt 27, transmitting the rotation of the pulley 25 to the pulley 26. The hub 28 of the pulley 25 is drawn over a sleeve 29, it being fixedly attached to said sleeve for instance by a screw 30. The sleeve is shiftably disposed upon the driving shaft and provided upon one of its ends with an enlargement 31, in which is seated a thrust-bearing 32, for a purpose hereinafter to be described. In one of the faces of the pulley 25 is provided an annular groove 33, adapted to receive a ring-shaped body 34 of a driving clutch member 35, that is keyed or otherwise fixedly attached to the driving shaft. Between the hub 36 of the driving clutch member and the adjacent bearing 22 is disposed a thrust bearing 37. The pulley 25 constitutes the driven clutch member of the apparatus.

The pulley 25 is disposed within a shield 38, that is attached to and supported by a tubular member 39. This tubular member surrounds the driving shaft and extends from the transmitting device 24 to the next bearing 22 in the series, to which it is attached by a coupling 40. That end of the tubular member 39 which is adjacent the shield 38 is kept concentrically in relation to the driving shaft by a bushing 41, fixed to the said tubular member.

45 The means for shifting the pulley 25, so as to engage with the driving clutch member, comprises a lever 42, that is fulcrumed at 43 to standards 44, the latter being either made integral with or fixedly attached to the shield 38. The arm 45 of this lever is fork-shaped and extends into the shield, its prongs bearing against the thrust-bearing 32. The other arm of the lever is connected by a rod 46 with a treadle 47 of any suitable construction. The lever 42 carries also a brake-block 48, which is adapted to reach within the belt receiving groove of the pulley 25, it being normally held within said groove by a spring 49, that is fixed to the said lever and the shield.

60 The operation of this device is as follows:—The driving shaft on the work-bench is rotating continuously and, in order to transmit its rotation to any one of the sewing-machine heads thereon, the respective

treadle is depressed, whereby the respective brake-block 48 is disengaged from the pulley 25 and the latter shifted into operative relation with the rotating driving clutch member 35. When in engagement, the rotation 70 of the said clutch member is transmitted to the pulley and thus to the sewing-machine head. By releasing the treadle, the spring 49 returns the lever 42 to the position shown in Fig. 3 of the drawings, whereby the pulley 75 is forced out of operative relation with the driving clutch member.

It is to be observed that the engaging and disengaging of the pulley 25 with the driving clutch member of any one of the power 80 transmitting devices on the work-bench does in no way affect the operation of the other power transmitting devices thereon, for the reason that the shifting mechanism is carried by a casing-like shield, which, in turn, 85 is mounted upon a tubular member 39, the latter being disposed in such a manner upon the driving shaft that it does in no way interfere with the rotation of the same or tend to transmit the shifting movement of 90 the clutch engaging means to the said shaft. The power transmitting devices on the bench are thus entirely independent of one another, and do in no way interfere with the independent operations of the several machine 95 operators. The endwise thrust of the several tubular members 39 is taken up by the bearings 22, to which they are connected, and the endwise thrust upon the driving clutch members 35 is taken up also by the 100 said bearings. The tubular members 39 serve, besides the functions mentioned, as a covering for the driving shaft, protecting the operators against accident.

It is to be observed that the clutch engaging means and brake of each power transmitting apparatus are mounted upon the cover-like shield thereof. It is thus impossible to actuate any power transmitting apparatus without having the protecting 110 shield over the rotary parts thereof. The operators are thus effectively guarded against accident.

The modification shown in Fig. 6 of the drawings, differs from the one above described mainly in that its driving clutch member 35 bears against a thrust bearing 37', that is disposed within an enlargement 39' of the tubular member 39. One of the rings 50 of this thrust bearing serves also to space the 120 unattached end of the tubular member 39 from the driving shaft. The bushing 41, to which the pulley 25 is fixed, abuts against a thrust-bearing 51, against the ring 52 of which lies the hub of the protecting 125 shield 38. The sleeve 53 is spaced from the driving shaft and is in engagement with the fork-shaped end of a bell-crank lever 54, that is fulcrumed at 55 to one of the legs 12 and connected by a rod 46 with a treadle. A 130

- spring 56, having one of its ends attached to the shield 38 and its other end to a hanger 23, serves to hold the elements in the positions shown in Fig. 6 of the drawings. The 5 brake-block 48, coöperating with the belt receiving groove of the pulley 25 is carried in this instance by a lever 57, that is fulcrumed at 58 to a leg 12 and connected by a link 59 with a lug 60 on the shield 38.
- 10 A shield 61 is secured to the tubular member 39 and incloses the thrust bearing 37 and the driving clutch member 35.

In order to transmit the rotation of the driving shaft to the pulley 25, the treadle 15 associated with the lever 54 is depressed, whereby the shield 38 is caused to move toward the driving clutch member 35, moving in the same direction the pulley until the latter is engaged by the driving clutch member. At the same time the lever 57 is lifted around its fulcrum 58, thereby disengaging the brake-block from the driving pulley. The spring 56 returns the parts to their 20 positions shown in Fig. 6 of the drawings, 25 when the treadle is released.

- The advantages of the device described in connection with the apparatus shown in Figs. 1 to 5, inclusive of the drawings are present in this modification also.
- 30 The modification, shown in Fig. 7 of the drawings, differs from the one illustrated in Fig. 6, in that the bearing 22, adjacent the transmitting device, is provided with a tubular extension 62, that is spaced from the 35 driving shaft and projects as far as the driving clutch member 35. The sleeve 53 is in this instance made, preferably, integral with the shield 38 and slidably mounted on the tubular extension 62. Furthermore, 40 the bushing 41 is missing and the hub of the pulley 25 slidably mounted upon the said tubular extension. The construction of this device is otherwise the same as of the modification shown in Fig. 6 of the drawings, 45 and so are also the function and operation of the mechanism the same.

The modification shown in Fig. 8 of the drawings differs slightly from the construction shown in Fig. 6. More particularly, in 50 this case the thrust bearing 37' of the driving clutch member 35 abuts against a bearing 22, and the thrust bearing 51 of the pulley 25 abuts against the tubular body 39. The shield 38 is in this instance fixedly attached to the said tubular member, the latter being shiftable and connected with the treadle rod 46 by a bell-crank lever 63, the latter being fulcrumed at 64 to a bracket 65, carried by a leg 12. Otherwise the construction is the same.

By depressing the treadle, the tubular body 39 is shifted, with the result that the clutch members are engaged and the brake disengaged. The spring 56 returns the ele-

ments to their positions shown in Fig. 8 of the drawings, when the treadle is released.

Attention is called to the fact that the driving clutch members, shown in the several figures of the drawings, are each attached to the driving shaft sections by a 70 key 100, that is seated in a keyway 101 in the said driving shaft section and in a slot 102 in the hub of the driving clutch member. Due to this arrangement, a thrust 75 against the driving clutch member will not be transmitted to the driving shaft sections, or in other words the operation of any one of the power transmitting apparatuses on the power bench will be independent of the others thereon.

What we claim is:—

1. In a power transmitting apparatus, the combination with two bearings, of a shaft 85 rotatably mounted therein, a driving clutch member on said shaft, means for fixing said driving clutch member to said shaft so as to prevent a thrust thereon to be transmitted to said shaft, a driven clutch member shiftable on said shaft in the direction of the longitudinal axis of the latter, a stationary tubular body encircling said shaft, 90 a shield for said driven clutch member fixed to said tubular body, and means in engagement with said driven clutch member for shifting the same so as to establish driving 95 connection between said clutch members, said shifting means being mounted upon said tubular body.

2. In a power transmitting apparatus, the combination with two bearings, of a shaft 100 rotatably mounted therein, a driving clutch member on said shaft adjacent one of said bearings, means for fixing said driving clutch member to said shaft so as to prevent a thrust thereon to be transmitted to said 105 shaft, a driven clutch member shiftable on said shaft in the direction of the longitudinal axis of the latter, a stationary tubular body encircling said shaft and extending from said driven clutch member to the other 110 one of said bearings, a shield for said driven clutch member fixed to said tubular body, and means in engagement with said driven clutch member for shifting the same so as to establish driving connection be- 115 tween said clutch members, said shifting means being mounted upon said tubular body.

3. A power transmitting apparatus according to claim 1, comprising a thrust 120 bearing inserted between said driving clutch member and the bearing adjacent the same, and a second thrust bearing abutting against said driven clutch member and said shifting means.

4. A power transmitting apparatus according to claim 2, comprising a thrust bearing inserted between said driving

4

clutch member and the bearing adjacent the same, and a second thrust bearing abutting against said driven clutch member and said shifting means.

5. A power transmitting apparatus according to claim 1, comprising a brake co-acting with said driven clutch member, said brake being carried by said tubular body.

6. A power transmitting apparatus according to claim 2, comprising a brake co-acting with said driven clutch member, said brake being carried by said tubular body.

7. In a power transmitting apparatus, the combination with two bearings, of a shaft 15 rotatably mounted therein, a driving clutch member on said shaft, means for fixing said driving clutch member to said shaft so as to prevent a thrust thereon to be transmitted to said shaft, a driven clutch member shift- 20 able on said shaft in the direction of the longitudinal axis of the latter, and shifting means for said driven clutch member mounted independently of said shaft.

8. In a power transmitting apparatus, the combination with two bearings, of a shaft 25 rotatably mounted therein, a driving clutch member fixed to said shaft, a driven clutch member shiftable on said shaft in the direction of the longitudinal axis of the latter, and co-operating shifting means and a brake 30 for said driven clutch member mounted independently of said shaft, said brake being movable in relation to said driven clutch member.

35. 9. In a power transmitting apparatus, the combination with two bearings, of a shaft rotatably mounted therein, a driving clutch member fixed to said shaft, a driven clutch member shiftable on said shaft in the direc- 40 tion of the longitudinal axis of the latter, a shield for said driven clutch member mounted independently of said shaft, and means in engagement with said shield for shifting

said driven clutch member into driving engagement with said driving clutch member. 45

10. In a power transmitting apparatus, the combination with two bearings, of a shaft rotatably mounted therein, a driving clutch member fixed to said shaft, a driven clutch member shiftable on said shaft in the 50 direction of the longitudinal axis of the latter, a shield for said clutch member mounted independently of said shaft, and co-acting shifting means and a brake for said driven clutch member in operative relation to said 55 shield so that by disengaging said shield the transmitting apparatus becomes inoperative.

11. In a power transmitting apparatus, the combination with a plurality of bearings, of a shaft rotatably journaled therein, a driving clutch member fixed to said shaft adjacent each bearing, a plurality of driven clutch members shiftable on said shaft in the 60 direction of the longitudinal axis of the latter, each driven clutch member being mounted adjacent its respective driving clutch member, a plurality of stationary tubular bodies encircling said shaft, each tubular body extending from the respective 65 driven clutch member to the next bearing in the series and being attached to the latter, a shield for each driven clutch member fixed to its respective tubular body, and independent means in engagement with each driven 70 clutch member for shifting the same so as to establish a driving connection between respective clutch members, each shifting means being mounted upon its respective tubular body.

Signed at New York, in the county of New York and State of New York, this 4th day of April A. D. 1919.

80
